UNITED STATES PATENT OFFICE

2,661,557

MULTIPLE MOVEMENT GATE

Alois Reymann, Sandwich, Ill.

Application April 26, 1951, Serial No. 222,995

1 Claim. (Cl. 39—76)

1

This invention relates to gates, and has particular reference to a novel and improved farm gate of such construction that it is inherently free of any tendency to sag, is easily adjustable as to ground clearance, may be securely latched at various degrees of ground clearance, and may be readily raised to clear snowdrifts, ice, or other obstructions such as might otherwise interfere with the swinging movement of the gate and prevent easy opening and closing thereof.

A specific object of the invention is to provide a gate structure wherein the gate is not only adjustable as to ground clearance, but is also adapted to be locked at various elevations, so that it may be set at a height such that it will prevent passage of large farm animals, yet permit the smaller farmyard animals to pass under it.

A still further object of the invention is the provision of a gate so designed and constructed that the gate frame is readily capable of vertical lifting as well as horizontal swinging movement, and so designed that sagging may be avoided even though the hinge post on which the gate is mounted should be pulled out of precise vertical alignment by the strains imposed upon it.

A still further object of the invention is the provision of a gate having means for affording vertical movement as well as swinging movement, with balancing devices whereby the weight of the gate is adequately supported in all positions; so that it may be easily raised or lowered without appreciable manual effort.

A still further object of the invention is the provision of a gate arranged for vertical shifting movement as well as lateral swinging, together with a gate latch mechanism of such design and construction as to permit engagement of the latch at any point within a wide range of vertical positions, and so constructed that the counterbalancing springs of the gate structure hold the latch against accidental release.

The foregoing objects are accomplished in the present invention by a gate having a unique arrangement of frame members wherein the vertical and the horizontal frame members are of rigid construction and arranged in intersecting relationship, but wherein the several individual members of the frame are pivoted to each other so that the entire assembly is free for vertical lifting movement as well as horizontal swinging movement. Thus the outer or free swinging end of the gate may be manually raised as the gate is opened, to bring the parts into upwardly inclined, diagonal relationship with each other

2

whereby the gate can swing clear of any obstructions such as accumulations of snow or ice in its normal path of swinging movement. The latch construction is so arranged that it may be released only after the free swinging end of the gate is manually lowered, as by bearing downwardly on one of the frame members thereof.

The preferred embodiment of the invention is illustrated in the drawings of the present specification, in which:

Figure 1 is a front elevational view of a gate as contemplated by this invention, the normal position of the frame elements thereof being illustrated in full lines and a raised position of the gate shown in dotted lines;

Figure 2 is a detail plan sectional view of the gate latch mechanism, the view being taken substantially on the plane of the line 2—2 of Figure 1;

Figure 3 is an enlarged detail sectional view of one of the pivotal joints between the horizontal frame members and the upright members of the frame;

Figure 4 is an enlarged detail plan view of the vertical supporting member of the gate and the hinge post on which the gate is mounted, with a fragmentary section of one of the horizontal frame members of the gate shown thereon; and

Figure 5 is an enlarged detail sectional view taken substantially on the plane of the line 5—5 of Figure 1, showing the lower end of the lifting link and the roller construction employed thereon.

The gate consists, in its essential parts, of a supporting member 10 comprising a heavy U-shaped metal channel (Figure 4) having hinge pins 11 and 12 at the upper and lower ends thereof whereby it is hinged to suitable brackets 13 and 14 on the gate post 15. The member 10 serves as a mounting for the cross frame members 16, 17, 18, 19 and 20, which may comprise wooden beams pivotally mounted to the supporting member 10 on bolts 21, 22, 23, 24 and 25, respectively. The frame of the gate also includes one or more upright frame members 26, each of which will be pivoted to the several horizontal members by bolts 27, 28, 29, 30 and 31. The bolts 27—31 are preferably each provided with a spacing sleeve 32 (Figure 3). These sleeves and bolts each extend through a bore in one of the longitudinal frame members so that the opposite frame members 26, which are preferably of angle iron, may be tightly bolted together, yet will be free for pivotal movement with respect to the horizontal wooden beams of the frame.

The gate includes a lifting link 33 and balance spring 34 to compensate for the weight of the frame and facilitate the manual shifting of the gate between the full line and dotted line positions shown. As illustrated, the lifting link 33 is pivoted to the supporting member 10 by the top bolt 21 thereon, and the lower end of the lifting link is provided with a cross bolt 35 on which a bushing 36 and roller 37 are carried. The bolt 35 also extends through a clevis 38 by which the balance spring 34 is attached to the link. The outer end of the balance spring 34 is secured to the frame by a bracket 39 and a tie bolt 40 having an adjusting nut 41 thereon to vary the tension exerted by the balance spring 34.

The latch mechanism of the gate includes a horizontal slide bar 42 mounted in brackets 43 on one of the horizontal frame members, and provided with a downwardly extending, manually operable handle 44. The forward end of the latch has a hooked end portion 45 which is adapted to engage a keeper on the gate post 43, as described more fully in my copending applications Ser. Nos. 690,726 and 38,820. The keeper consists of a vertical angle iron 47 and parallel bar 48 between which the hooked end 45 of the latch bolt may engage. It is preferred, however, to provide vertical stop portions 49 at intervals along the angle iron, so that the hooked end portion 45 of the latch bar will bear against the surface of one of the stops, so that the latch not only limits the vertical movement of the gate, but is at the same time self-locking. That is, the contact between the hooked end 45 and the stops 49 prevents inadvertent rotation of the latch bolt, and this provides an adequate safeguard against accidental release. Intentional release of the latch is, of course, easily accomplished by manually shifting the frame members of the gate sufficiently to allow the end of the latch 45 to clear the stops 49, and then lifting the manual handle 44 and withdrawing the latch bolt from the keeper. When lifted to the dotted line position shown in Figure 1, the gate will easily clear obstructions such as snowdrifts 50.

It will be seen from the above that inasmuch as the frame members of the gate are pivoted to each other in a flexible manner and are provided with a balancing spring, there will be no tendency for the gate to sag even in the event that the hinge post should be pulled out of precise vertical alignment. Moreover, the outer end of the gate may be raised or lowered manually to provide any required amount of ground

clearance. The structure is so designed that it may be lifted to a considerable height if necessary in order to clear obstructions such as snow or ice which may accumulate in its normal path of horizontal swinging movement. It is, at the same time, comparatively simple and easy to assemble and is sufficiently inexpensive to manufacture as to be practicable from a commercial standpoint.

Having thus described my invention, what I claim as new and desire to secure by United States Letters Patent is:

A gate comprising in combination, a supporting member consisting of a U-shaped metallic channel having a pair of hinge pins at the upper and lower ends thereof, with a plurality of bolts extending between the flanges at vertically spaced intervals; a plurality of wooden beams each having one end portion disposed between said flanges and pivoted on the aforesaid bolts and extending outwardly therefrom in parallel relation to each other; a plurality of upright frame members disposed in co-acting pairs on the front and back faces of said beams, with each of said upright frame members extending across each of the beams and being pivoted thereto by bolts extending between the frame members and passing through spacing sleeves received in pivotal apertures of each of said beams; with a pair of lifting links pivotally connected to one of the aforementioned bolts on the supporting member, said links extending downwardly and outwardly from said bolt in parallel relationship and on the opposite sides of at least one of said beams; a roller between the lower ends of said links adapted to engage one of said beams on its lower surface to urge the gate upwardly, and a balance spring horizontally disposed between adjacent beams and extending outwardly from said roller, whereby the action of said roller and links will exert an upward component of force on the gate.

ALOIS REYMANN.
